US0D1110907S

(12) **United States Design Patent** (10) **Patent No.:** **US D1,110,907 S**
(45) **Date of Patent:** **** Feb. 3, 2026**

(54) **STEERING WHEEL**

(71) Applicant: **Gordon Murray Automotive Limited**, Shalford (GB)

(72) Inventor: **Ian Gordon Murray**, Puttenham (GB)

(73) Assignee: **Gordon Murray Automotive Limited**, Shalford (GB)

(**) Term: **15 Years**

(21) Appl. No.: **29/947,965**

(22) Filed: **Jun. 18, 2024**

Related U.S. Application Data

(62) Division of application No. 29/850,466, filed on Aug. 19, 2022, now Pat. No. Des. 1,074,545.
